CARRYING CASE FOR A CAMERA OR SIMILAR ARTICLE

Vincent F. Lang, Greece, and Edward Emison, Ontario,
N.Y., assignors to Eastman Kodak Company, Rochester, N.Y., a corporation of New Jersey

Filed Feb. 12, 1969, Ser. No. 15,746

Term of patent 14 years

Int. Cl. D3—99

U.S. Cl. D87—5

FIG. 1

FIG. 2

FIG. 3

FIG. 5

FIG. 1 is a front, top, and right-side perspective view of a carrying case for a camera or similar article, showing our new design with the cover thereof in closed position;

FIG. 2 is a rear elevational view;

FIG. 3 is a left-side elevational view, the right side being substantially a mirror image thereof;

FIG. 4 is a bottom plan view; and

FIG. 5 is a front, top, and right-side perspective view with the cover in open position.

The carrying strap shown in FIG. 1 has been omitted from the remaining figures for convenience in illustration.

We claim:

The ornamental design for a carrying case for a camera or similar article, as shown and described.
